United States Patent Office

Des. 220,886
Patented June 8, 1971

220,886

SPECTACLE FRAME FRONT

Richard R. Maiese, Webster, and Harold F. Whiting,
Attleboro, Mass., assignors to American Optical Cor-
poration, Southbridge, Mass.

Filed Mar. 25, 1970, Ser. No. 22,055

Term of patent 7 years

Int. Cl. D16—08

U.S. Cl. D57—1

FIG. 1

FIG. 2

FIG. 3

FIG. 1 is a front elevational view of a spectacle frame front embodying my new design;

FIG. 2 is a top plan view thereof; and

FIG. 3 is an enlarged fragmentary elevational view of a part of the spectacle frame front of FIG. 1.

I claim:

The ornamental design for a spectacle frame front, as shown and described.
